(Cl. D34—13)

To all whom it may concern:

Be it known that I, Clifford Benjamin Griffiths, a British subject residing at Sutton Coldfield, Warwickshire, England, have invented a new, original, and ornamental Design, for a Set of Playing Cards, of which the following is a specification, reference being had to the accompanying drawing, forming a part hereof.

The single figure is a face view of four cards in a set of playing cards, showing my new design. The set of playing cards consists of 60 cards. The remaining 56 cards, not shown, consist of a conventional deck of 52 playing cards and 4 conventional jokers.

The cards are of no appreciable thickness, and the backs thereof are conventional.

I claim:

The ornamental design for a set of playing cards, as shown and described.

CLIFFORD BENJAMIN GRIFFITHS.
